UNITED STATES PATENT OFFICE.

ALBERT E. LYITLE, OF CHICAGO, ILLINOIS, ASSIGNOR OF ONE-HALF TO
HERCULES F. DOUSMAN, OF CHICAGO, ILLINOIS.

ELECTRIC CONDUCTOR.

SPECIFICATION forming part of Letters Patent No. 744,926, dated November 24, 1903.

Application filed April 20, 1901. Renewed October 1, 1903. Serial No. 175,323. (No model.)

To all whom it may concern:

Be it known that I, ALBERT E. LYITLE, a citizen of the United States, residing at Chicago, in the county of Cook and State of Illinois, 5 have invented certain new and useful Improvements in Electric Conductors, of which the following is a specification.

This invention relates to improvements in that class of conductors known as "trolley-wires," used in electric-railway systems; and it consists in certain novel features of the construction and arrangement of the parts thereof, as will be hereinafter more fully set forth and specifically claimed.

15 The principal object of the invention is to provide simple and efficient means for connecting or coupling sections of the conductor together.

In order to enable others skilled in the art 20 to which my invention pertains to make and use the same, I will now proceed to describe it, referring to the accompanying drawings, in which—

Figure 1 is a perspective view of a portion 25 of an electric conductor embodying my invention, showing the two sections thereof coupled together and supported on a cross-wire by means of an insulator. Fig. 2 is an enlarged plan view in elevation of two sections of the 30 conductor coupled together; and Fig. 3 is a view in side elevation thereof, partly in section.

Similar letters refer to like parts throughout the different views of the drawings.

35 A and A' represent two sections of the conductor, which are made hollow and of copper or other suitable electric conducting material. The adjacent ends of the sections A and A' are provided internally with right and left 40 screw-threads *a* and *a'*, respectively, to engage suitably-formed screw-threads *b* and *b'* on the ends of the coupling-piece B, which unites the sections, as is shown in the drawings. The coupling B is preferably hollow

45 and has its extremities reduced and screw-threaded, as above stated, and is formed at the inner ends of the screw-threads with

shoulders *c*, against which the adjacent ends of the conductors will abut, thus forming a close joint and substantially a continuous 50 piece or conductor. When the sections of the conductor are screwed on the reduced and screw-threaded portions of the coupling, the intermediate portion of which is preferably of the same size as that of the sections, it is 55 apparent that a smooth and substantially unbroken hollow conductor is provided. The coupling B is formed at about its middle with an extension B', the free portion of which is externally screw-threaded to engage an insulator C, which may be of the ordinary or any 60 preferred construction and may be supported by means of a cross-wire D or otherwise. To save material and also lessen the weight of the coupling, as well as to obtain better con- 65 ductive effect, the extension B' and conductor B are preferably made hollow, and the hollow of the extension preferably communicates with the hollow coupling. However, I may sometimes make them of solid material or 70 may make the coupling hollow and the extension solid or the extension hollow and the coupling solid without departing from the spirit of my invention. Where sections of the conductor are to be joined together and 75 it is not desired to support them at their juncture, a coupling without extension B' may be employed, and when such is the case the coupling may be hollow or solid.

Having thus fully described my invention, 80 what I claim as new, and desire to secure by Letters Patent, is—

An electric conductor comprising hollow sections provided at their ends to be joined together with internal screw-threads, and a 85 hollow coupling having on its extremities screw-threads to engage those of the sections, and between its extremities an extension having means to engage a support, substantially as described.

ALBERT E. LYITLE.
